UNITED STATES PATENT OFFICE.

DAVID A. KIDWELL, OF PORTALES, NEW MEXICO.

FEED HOLDER.

Application filed June 12, 1923. Serial No. 644,928.

To all whom it may concern:

Be it known that I, DAVID A. KIDWELL, a citizen of the United States, residing at Portales, in the county of Roosevelt and 5 State of New Mexico, have invented certain new and useful Improvements in Feed Holders; and I do hereby declare the following to be a full, clear, and exact description of the invention, such as will enable others 10 skilled in the art to which it appertains to make and use the same.

This invention has relation to stock feeding and has for its object to hold the feed in such manner as to prevent waste thereof, or 15 the trampling of the same under foot, or the scattering thereof.

A further purpose of the invention is the provision of a holder for securing feed of the nature usually fed in bundles or bunches, 20 such feed being positively held in the required position with the result that waste is practically prevented.

Other objects and advantages will be apparent and suggest themselves as the nature 25 of the invention is understood.

While the drawings illustrate an embodiment of the invention it is to be understood that in adapting the same to meet different conditions and requirements, various changes 30 in the form, proportion and minor details of construction may be resorted to without departing from the nature of the invention.

Referring to the accompanying drawings forming a part of the application:

35 Figure 1 is a perspective view illustrative of the invention,

Figure 2 is a perspective view of the holder as seen from the rear,

Figure 3 is a horizontal section on the line 40 3—3 of Figure 1;

Figure 4 is a front view of a modification,

Figure 5 is a perspective view of a further modification, and

Figure 6 is a sectional view of a still further modification.

Corresponding and like parts are referred to in the following description and designated in the several views of the drawings by like reference characters.

50 The numeral 1 designates a suitable support, such as a post, fence, trough, manger or other convenient means. A short crossbar 2 is attached to the support, preferably by means of a short chain 3 and hook bolts 4, the latter passing through slots 5 formed in opposite end portions of the crossbar 2.

The crossbar 2 is placed against one side of the support and the chain 3 is placed against the opposite side, the hook bolts 4 passing through the slots 5 and engaging links at opposite ends of the chain 3, and after the parts are arranged they are secured by tightening the nuts upon the bolts. The slots 5 provide for adjustment whereby to adapt the holder to different supports. 60 65

A hook 6 is applied to an end portion of the crossbar 2 and a pulley 7 is provided at the opposite end of the crossbar. A binder 8, consisting of a length of chain, is adapted to be detachably connected to the hook 6 at 70 one end and its opposite end portion engages the pulley 7. A suitable catch 9 is provided at the end of the crossbar 2 adjacent the pulley 7 and engages a link of the chain 8 to secure the same in the required 75 position.

In practice, a bundle, sheaf or bunch 10 of feed is placed against the crossbar 2 and the chain 8 previously disengaged from the hook 6 is passed around the bunch 10 and engaged 80 with the hook 6, the feed being confined between the crossbar 2 and the binder or chain 8. The loose end of the binder or chain 8 is drawn upon to tighten the binder about the feed and after the chain has been sufficiently 85 tightened, it is secured by engaging a link with the catch 9. It will thus be understood that the feed is held securely and is drawn from the bunch as consumed, thereby preventing scattering or the trampling thereof 90 under foot.

The feed may be held in upright or horizontal position, as required, and as indicated in Figures 4 and 5.

When the invention is applied to a wall, 95 fence, manger or the like, the chain 3 is dispensed with and the hook bolts 4 are passed through openings formed in the wall 1^a, or like part, and receive washers 11 and nuts 12, the parts 1^a and 2 being clamped between 100 the washers 11 and nuts 12. This is shown most clearly in Figure 6.

What is claimed is:

1. A feed holder comprising a flexible support, a binder, detachably engaging the 105 support at one end, a guide at the opposite support at the other end engaged by the binder adjacent the other end thereof when the latter end is unfastened, and a catch upon the support adjacent the guide to engage and hold the binder in the required adjusted position. 110

- 2
2. A feed holder comprising a bar, a binder, means detachably connecting the binder at one end with an end portion of the bar, a guide pulley at the opposite end of the bar to loosely engage the opposite end portion of the binder, and a catch on the bar adjacent the guide pulley to engage and hold the binder in the required adjusted position.
  3. A feed holder comprising a bar having 10 longitudinally disposed slots in opposite end portions, hook bolts engaging said slots, a connection engaging the hook bolts, a binder chain, a hook at one end of the bar to detachably engage an end portion of the binder

chain, a guide pulley at the opposite end of 15 the bar loosely engaging the opposite end portion of the binder chain, and a catch at the end of the bar adjacent the guide pulley to engage a link of the binder chain and secure the same in the required adjusted position. 20

In testimony whereof I affix my signature in presence of two witnesses.

DAVID A. KIDWELL.
